Primary Examiner — Joseph Kukella*Assistant Examiner* — Heather Wencl(74) *Attorney, Agent, or Firm* — John Rizvi; John Rizvi, P.A.—The Patent Professor ®(57) **CLAIM**

The ornamental design for a fencing stationary security device, as shown and described.

DESCRIPTION

FIG. 1 is a front, right side perspective view of the fencing stationary security device, showing my new design;
 FIG. 2 is a rear, left side perspective view thereof;
 FIG. 3 is a front elevation view thereof;
 FIG. 4 is a rear elevation view thereof;
 FIG. 5 is a right side sectional view thereof;
 FIG. 6 is a left side sectional view thereof;
 FIG. 7 is a top sectional view thereof; and,
 FIG. 8 is a bottom sectional view thereof.

The portion of the fencing stationary security device depicted in the figures in broken lines forms no part of the claimed design.
